UNITED STATES PATENT OFFICE.

LUCIUS E. MILES, OF JANESVILLE, ASSIGNOR OF ONE-HALF TO ISAAC MILES,
OF FULTON, WISCONSIN.

HAY ELEVATOR AND CARRIER.

SPECIFICATION forming part of Letters Patent No. 248,873, dated November 1, 1881.

Application filed September 13, 1881. (Model.)

To all whom it may concern:

Be it known that I, LUCIUS E. MILES, of Janesville, in the county of Rock and State of Wisconsin, have invented certain new and useful Improvements in Hay Elevators and Carriers; and I do hereby declare the following to be a full, clear, and exact description of the invention, such as will enable others skilled in the art to which it pertains to make and use the same.

My invention relates to an improvement in hay elevators and carriers, the object of the same being to provide strong and durable mechanism for holding the car stationary while the hay is being elevated to any desired height, carrying the same any desired distance, automatically returning the car to its original position and locking it, and automatically releasing the loose pulley, thereby allowing it to de-
scend for another load.

With these ends in view my invention consists in certain details in construction and combinations of parts as will be more fully explained and pointed out in the claims.

In the accompanying drawings, Figure 1 is a side elevation of my improved elevator and carrier. Fig. 2 is a longitudinal vertical section through the track and car. Fig. 3 is a transverse vertical section through the jaws of the car. Fig. 4 is an end view. Fig. 5 is a view taken through the pulley in the forward end of the car, and Fig. 6 is a detached view of the tongue.

A represents a ridge-pole of a barn, or a beam adapted especially for the purpose, suspended or supported in any suitable manner and adapted to form a track or runway for the carriage B. This beam A is provided with pulleys C on the opposite ends thereof around which the draft-rope D passes. The car or carriage B is suspended on the under side of the track A in close proximity thereto by the metallic straps E, which latter are adapted to embrace the lower face and two sides of the car or carriage B and hold the parts composing the said carriage firmly in position while the said parts are still further strengthened by the bolts a, which latter are adapted to pass through the straps E and carriage B and prevent the parts from spreading outward, while the me-

tallic lips F and plate c' prevent the parts from being clamped too near together, which would hold the tongue G and pulley H firmly therein and prevent them from performing the respective functions. The upper ends of the metallic straps E are bent, as shown in the drawings, to form bearings for the friction-wheels c.

The car B is made of two parts secured together, as above described, with an open space between into which the pulley H and the tongue G are loosely secured. The pulley H is situated in the front part of the carriage B and journaled on the bolt a, which latter aids in securing the parts together, as above described.

The jaws I are pivoted to the plate c' in the upper side of the carriage, and are adapted to engage with and hold the loose pulley J well up under the same. These jaws I work in grooves cut in the side pieces of the carriage, and are adapted, when free, to come together and hold the block securely therein until automatically released by the sliding tongue G. This tongue G moves horizontally in the space between the side pieces of the carriage, and is provided with two arms, d, each having an oblong slot, d', therein through which the bolt a, having the pulley H thereon, passes, the said pulley H resting between the two arms. This bolt a holds the rear end of the tongue in position while the free end is retained in a horizontal position by the other bolt, a', on which the tongue rests. That portion of the tongue G immediately in front of the arms d is narrowed considerably, and is provided with a vertical slot, K, in which the pointed end e of the head M of the loose pulley J rests when the latter is in position, and is prevented thereby from turning and becoming disengaged from the jaws. When this narrowed portion of the tongue rests between the opposing faces of the jaws I there is sufficient space left for the jaws to touch each other; but when the carriage reaches the end of the runway A and the shoulders f near the extreme outer end of the tongue abut against the sides of the stop N, the tongue is forced further in the carriage, and the inclined and the thickened portion of the tongue is pressed between the jaws I, which forces them apart and allows the block J to

be released, and descend for another load. As soon as the latch *f* passes the stop *N* it engages therewith and holds the carriage in position until the fork has been refilled.

5 The carriage *B* is automatically released from the stop by the loose pulley *J* lifting the tongue *G*, and the power used in elevating the load is transferred to moving the car, which draws it forward until the proper position is 10 reached, when the load is released from the fork by a cord or any suitable arrangement. The loose pulley-block *J* is provided with the oblong loop adapted to prevent the block from turning upside down while ascending to the 15 carriage. This loop *J'* is adapted to fit on the outside of the block, substantially as shown, and is secured thereto by the bolt *O*, which forms the journal for the pulley. At the rear end of the car is attached a rope, *P*, which 20 passes over the pulley *Q* located on the under side of the track *A*, near its rear end, and is provided with any suitable weight to draw the car back to its original position after the fork has been released.

25 The draft-rope *D* is secured at one end to the carriage, and then passes through the loose pulley *J*, and from thence over the wheel *H*, under wheel *C*, and over wheel *C*, and thence down to where the operator stands. After the 30 fork attached to the swiveled hook *g* in the lower end of the block has been loaded the loose pulley is drawn up by any suitable power until the upper end of the block enters between the jaws. When the head of this block 35 *J* strikes the tongue *G* it raises it and releases the catch and allows the carriage to travel in the direction of the draft, when the load can be released from the fork in any desired manner by the operator. The power on the draft- 40 rope *D* is now withdrawn and the carriage is allowed to run back to its original position with the pulley-block secured between the jaws. When the car or carriage reaches the 45 stop *N* the shoulders *f* on the tongue *G* abut against the stop *N*, which carries the tongue inward until the inclined sides thereof open the jaws, which allows the loose pulley holding the hay-fork to drop over the load to be reloaded.

50 For the purpose of facilitating the engagement of the loose pulley with the carriage, I have provided two lips, *F*, adapted to be secured to the opposite sides of the carriage on the opposite sides of the jaws. These lips *F* 55 are provided with inclined faces, which, together with the inclined faces of the jaws, form a flaring-mouth, which most effectually guides the head of the loose pulley between the jaws. After the head of the loose pulley 60 has engaged the jaws it is prevented from turning therein by the pointed end of the head entering the oblong slot *R* in the tongue *G*.

The stop *N* is constructed precisely alike on both sides, so that it will be unnecessary to 65 turn it around when the carrier is used on the opposite end of the beam *A*.

The car or carriage can be made entirely of

iron, if desired, but I prefer to construct the sides of wood and the rest of metal, as it makes it less expensive, while at the same time strong enough for all necessary purposes. 70

My improved construction is susceptible of numerous changes, and hence I would have it understood that I do not limit myself to the exact construction of parts shown and described, but consider myself at liberty to make such changes as come within the spirit and scope of my invention. 75

Having fully described my invention, what I claim as new and desire to secure by Letters 80 Patent, is—

1. In a combined hay elevator and carrier, the combination, with the beam having pulleys secured therein and a stationary stop secured to its underside, of a car or carriage constructed as described, and provided with two swinging jaws, a longitudinally-sliding tongue provided with an oblong slot and inclined sides, and a catch, a draft-rope, and a pulley-block having shoulders adapted to rest on the jaws 90 and a pointed end to rest in the oblong slot in the tongue, substantially as set forth. 95

2. In a combined hay elevator and carrier, the combination, with a beam having pulleys secured therein and a stop secured thereto, of a carriage constructed as described, having jaws hinged to a plate, the latter being secured between the sides of the carriage, a sliding tongue having inclined sides and an oblong slot, two lips secured to the carriage on opposite sides of the jaws, a draft-rope, and a block having shoulders thereon adapted to rest in the jaws, and a pointed end adapted to fit in the oblong slot in the tongue to prevent the block from turning, substantially as set forth. 100

3. In a combined hay elevator and carrier, the combination, with the beam having pulleys secured therein and a two-faced stop secured thereto on its under side, of a carriage constructed as described, and provided with binged jaws, a sliding tongue having two arms provided with oblong slots through which a bolt passes, inclined sides for separating the jaws, and an oblong slot, a draft-rope, a pulley-block having shoulders adapted to rest in the jaws, 115 and a pointed head to rest in the oblong slot, and a rope having a weight secured thereto for drawing back the carriage after the load has been deposited, substantially as set forth. 120

4. The combination, with the beam and carriage constructed as described, of the sliding tongue, provided with a catch adapted to hold the carriage in position while the load is being elevated, with inclined sides for automatically releasing the pulley-block, and an oblong slot 125 for holding the pulley-block in position in the carriage, substantially as set forth.

In testimony whereof I have signed this specification in the presence of two subscribing witnesses.

LUCIUS E. MILES.
